LACROSSE RACQUET

Frederic C. Jay, Baltimore, Md., assignor to
 Kentucky Forest Products, Inc., Baltimore, Md.,
 a corporation of Maryland

Application September 9, 1948, Serial No. 48,423

8 Claims. (Cl. 273—96)

1

This invention relates to athletic devices, more specifically, to improvements in lacrosse sticks.

Lacrosse sticks or racquets have been made for generations under certain methods adopted by the Indians of Canada and with certain tools considered appropriate for many years. Since lacrosse racquets are thereby made by hand they are generally not uniform in shape. The materials, being produced under natural conditions without scientific selection, are likewise variable in their finished form, that is, the strings or strips in one case may be stretched taut and in another case they may be loose even though apparently made under the same conditions.

An outstanding disadvantage of lacrosse racquets is that the stick, which is generally carved out by hand from a piece of wood, is not uniform in strength throughout the length thereof, and, instead, has shear points because of imperfections in carving or the presence of knot holes, etc. Moreover, even though bent into somewhat L-shape, the framework does not retain such shape and instead warps causing a change in the tension of the netting. Moreover, the conventional type of guard used is not satisfactory because the spacer elements are generally made of flexible gut-like material which curls in time, therefore not only reducing the height of the guard but curling the top edge inwardly and thereby reducing the effective ball catching area of the lacrosse stick. In some instances, the top edge bows outwardly and thereby increases such ball catching area. In short, no uniformity is maintained in the ball catching area, or in the rigidity and height of the guard.

An object of the present invention is to overcome the above-named disadvantages of common types of lacrosse sticks.

A more specific object of this invention is to provide a novel lacrosse stick having a frame work made of laminated wood glued together, so as to considerably increase the strength and uniformity of the frame work and eliminate shear spots, as well as to make a frame work that will retain its shape even after extensive use or play of the lacrosse stick.

A further specific object of the present invention is to provide, in a lacrosse stock, a novel guard structure including a plurality of stiff spacer members, or posts, for preventing curling of the guard and for insuring uniform height of the guard as well as uniform ball catching area of the netting.

A still further object of this invention is to provide a novel attaching lacing for firmly hold-

2

ing the netting to the back of the lacrosse stick by a plurality of spaced points each of which securely anchors the netting in place, thereby insuring uniformity of tension of the netting.

- 5 A still further object of the invention is to provide a lacrosse racquet or stick which is scientifically reproducible, so as to standardize all sticks and give exactly similar characteristics, shapes, sizes, weights and proportions and thus 10 avoid the necessity for players to get used to a particular stick, as is commonly the case with present lacrosse racquets, since the handmaking thereof invariably causes different characteristics for different sticks.
- 15 Other objects and advantages will become apparent from the following specification taken with the accompanying drawing wherein:

Figure 1 is a top or plan view of a lacrosse stick embodying the principles of the present invention;

20 Figure 2 is an enlarged side view of the guard side of the lacrosse stick shown in Figure 1, shown partly broken away;

Figure 3 is a bottom view of the lacrosse stick shown in Figures 1 and 2;

25 Figure 4 is an enlarged sectional view of the handle taken along line 4—4 of Figure 3 and more clearly showing the laminated construction thereof; and

Figure 5 is an enlarged perspective view of one 30 of the posts shown in Figure 2.

Referring more particularly to the drawings, numeral 1 generally denotes an L-like frame having a handle portion 2, a back portion 3, a lip portion 4 and a toe portion 5. An important 35 feature of the present invention resides in making the frame of the lacrosse stick or racquet of laminated wood. American birch, northern elm or white ash are among the woods that have been found to give highly satisfactory results 40 although it will be understood that other woods are equally useful. The wood strips or laminations are glued together by any suitable thermosetting glue and the laminations are bent into somewhat L-shape. The toe portion 5 is torsionally bent inwardly as shown in the drawing. The handle portion 1 is somewhat elliptical in cross section as shown more clearly in Figure 4 and increases in height or depth at the crotch 6, that is, at the beginning of the back portion, and retains such increased height throughout the entire 45 back portion 3 and then gradually tapers to a shorter height of about one-third of the height of the back portion along lip portion 4. By so varying the height throughout the length of the 50 racquet, the racquet is strengthened at places

where greatest strength is required and reduced in height where reinforcement is not necessary, thereby providing not only a strong but relatively light stick. The back portion is also curved on the outside surface thereof as well as inclined so as to form an acute angle with the major plane of the handle portion. Each of the laminations extends throughout the entire length of the stick, that is from the end of the handle to the extreme end of the toe so as to insure uniformity of cross section along the different portions, for example along the handle portion, so as to give better balance and ease of carrying the stick. The lip portion 4 is tapered inwardly or scooped and the end portion of the toe is elevated so as to correspond in height to the top edge of the back at the crotch portion 6.

Netting 8 is strung and the ends thereof extend through holes such as 9 formed along the length of the back and lip portion. A plurality of longitudinally extending thongs or lead wires 10 are provided, the top ends of which are securely anchored to the lip portion 4 and the bottom ends of which are tied to the back adjacent the crotch portion 6. Four such longitudinally extending thongs are shown, as is conventional. Instead of tying in the ends of the netting loosely along the back as is commonly done they are tied in at a plurality of spaced points by the attaching lacing 11, while attaching lacing 11 is somewhat in the form of a lock stitch or other suitable lacing to provide a positive tie in at a plurality of points instead of at the two ends as is common in the art. This plurality of anchoring points insures uniformity of tension of the netting and eliminates abnormal pockets or sagging of the netting as would otherwise occur.

Another important feature of the present invention resides in the guard structure which is shown more clearly in Figure 2 and which comprises a plurality of strands of babiche or raw hide 12 which run longitudinally of the frame and extend between the holes formed in the toe portion and those formed at the crotch portion of the stick or frame work. Instead of providing a plurality of flexible spacers, there are provided a plurality of stiff spacers or posts 13 for maintaining uniform space between the outer longitudinally running strands of the guard. The spacers or posts are preferably made of fibrous material such as vulcanized fiber or phenolic treated canvas. The ends of the posts 13 are notched at 13a (see Figure 5), so that the outside strands of the guard may extend therethrough and be firmly anchored and held tensioned in substantially a straight line without the necessity of tie-ins or knots at each post. The end strands of the guard are protected by spirally wrapping therearound babiche or other suitable gut or flexible material to form a protective covering as shown in Figure 2. Adjacent the crotch portion 6 there is strung a stop guard 14 made by stringing or bridging babiche between the back portion and the top edge of the end post, there being an additional strand of babiche extending from the central part of such bridge and the lower central portion of the netting 8.

Thus, it will be seen that I have provided a highly efficient, strong but relatively light lacrosse stick or racquet whose frame is made of wooden laminations and therefore the cross section of which is uniform throughout the lengths of the various portions, giving greater balance of the handle portion as well as greater permanency in retaining the original shape of the frame work,

and minimizing the common tendency of the angularly bent lip portion to become distorted with age and usage. Also, I have provided a novel guard structure wherein rigid posts or spacer elements are provided to insure uniformity in height through the length of the guard as well as to insure that the guard will maintain a position in a plane at right angles to the netting to thereby insure that the ball catching area of the netting will always remain constant instead of varying in size by the inward or outward bending of the guard as is common in the art giving undue advantage or disadvantage to the players. Additionally by making the framework of laminated wood and by insuring retention of shape through long periods of usage as well as insuring uniformity in cross section throughout different portions of the length of the stick, there is provided, for the first time in the art, a truly uniform stick which players may accustom themselves to using and which, if broken and replaced, the characteristics of the replacement will be exactly the same. This is in contrast to the use of well known sticks wherein a player has to become used to or become broken in to the peculiar idiosyncrasies of a given stick and in case of breakage will be forced to remain out of the game inasmuch as it would take a considerable length of time for him to get used to the different characteristics of a new stick.

While there is illustrated and described a single specific embodiment of the invention, it will be understood that this is by way of illustration only and that various changes and modifications may be made within the spirit and purview of the invention and within the scope of the following claims.

I claim:

1. A lacrosse racquet comprising in combination a frame having a handle, a back portion of greater height than that of the handle, a lip portion, and a toe portion, said portions forming substantially an L-shaped frame, said toe portion being bent at right angles to the lip portion and disposed to lie within the projected area of the longitudinal edges of said back portion, and netting strung between said back, lip and toe portions having a guard extending between the toe portion and the back portion of said frame, said guard comprising a plurality of spaced substantially rigid posts separating vertically a plurality of strands of flexible material extending between said toe and back portions at a spacing greater than the height of said toe and approximating that of said back portion to retain said guard in a flat plane configuration against material displacement.

2. A lacrosse racquet comprising in combination, a handle having a substantially L-shaped frame formed at an end thereof by back, lip and toe portions, said back portion having greater height than the handle portion throughout the length thereof, said lip portion extending generally perpendicularly to said back portion and ending in said toe portion extending at right angles to the lip portion and lying within the right angular projected area of the longitudinal edges of said back portion, and netting strung between said frame portions having a guard extending perpendicularly thereto between said toe and back portions, said guard comprising a plurality of spaced parallel substantially rigid posts separating vertically a plurality of strands of flexible material extending between said toe and back portions at a spacing greater than the

height of said toe and approximating that of said back portion to retain said guard in a flat plane configuration against material displacement.

3. A lacrosse racquet comprising in combination a frame having a handle, a back portion, a lip portion, and a toe portion, said back portion having greater height than the handle portion throughout the length thereof, said lip portion extending substantially at right angles to said back portion and ending in said toe portion partially bent at right angles to the lip portion and disposed to lie within the right angular projected area of the longitudinal edges of said back portion, and netting strung between said back, lip and toe portions having a guard strung between the end of the toe portion and juncture between the back and handle portions of said lacrosse stick, said guards comprising a plurality of longitudinally extending strands of flexible material disposed perpendicularly relative to said netting having a plurality of spaced parallel posts extending at right angles thereto having perforations through which said strands extend, the ends of said posts being notched through which the outermost longitudinally extending strands traverse, said posts being of a material highly resistant to deformation forces directed transversely to said guard and being resiliently yieldable to deformation in the direction of the principal longitudinal axis of said posts for retaining said guard on a flat plane configuration of a height substantially corresponding to that of said back portion at all times.

4. In a lacrosse racquet, the combination set forth in claim 3 wherein said guard posts are made of vulcanized fibre.

5. In a lacrosse racquet, the combination as set forth in claim 3 wherein said guard posts are made of phenolic treated canvas.

6. A lacrosse racquet comprising a framework made of wooden laminations, all the laminations of which extend throughout the entire length of the framework, said framework comprising a handle portion having substantially elliptical cross section, a back portion having a greater height than the handle portion and curved along

the outer surface thereof, a lip portion extending substantially at right angles to the back portion and tapering down to a height of about one-third of that of the back portion and ending in a toe portion tortionally bent substantially at right angles to the lip portion and disposed on an axis such that the toe portion falls within the limits defined by the right angular projections of the longitudinal edges of said back portion, a netting strung between said back, lip and toe portions, and a guard strung between the juncture of the back and handle portions and the toe portion, said guard comprising a plurality of flexible strands extending longitudinally in substantially spaced parallel relationship, a plurality of posts extending at right angles to said longitudinal strands and having perforations through which the innermost of said strands extend, the extreme ends of said posts having notches through which the outermost of said longitudinal strands extend, said posts being of substantially greater height than that of the free end of said toe portion relative to the juncture between said toe and lip portion for maintaining said guard in a flat plane configuration extending at right angles to said netting and of a height approximating that of said back portion to provide a constant ball catching area of said netting.

7. A lacrosse racquet as set forth in the next preceding claim wherein said guard posts are made of vulcanized fiber.

8. A lacrosse racquet as set forth in claim 6, wherein said guard posts are made of phenolic treated canvas.
